UNITED STATES PATENT OFFICE.

CYRUS A. DODGE, OF SYRACUSE, NEW YORK.

WASHING-MACHINE.

No. 834,370.

Specification of Letters Patent.

Patented Oct. 30, 1906.

Application filed October 6, 1903. Serial No. 175,913.

To all whom it may concern:

Be it known that I, CYRUS A. DODGE, a citizen of the United States, residing at Syracuse, in the county of Onondaga and State of New York, have invented certain new and useful Improvements in Washing-Machines; and I do hereby declare the following to be a full, clear, and exact description of the invention, such as will enable others skilled in the art to which it appertains to make and use the same.

My invention relates to improvements in washing-machines, and more particularly to those of the "pounder" type.

One object of my present invention is to provide simple and efficient means for adapting a pounder washing-machine for use with "set" or fixed tubs having sloping front walls.

A further object is to provide means for mounting the operating means of a pounder washing-machine within a tub.

A further object is to so construct a pounder washing-machine that its operating mechanism can be located within a tub of any size or shape and so that all parts of the tub can be readily reached by the pounder.

A further object is to provide a construction which will admit of the use of an angular lever for operating the pounder and moving the latter to any desired position within the tub.

A further object is to provide simple means for attaching a pounder-machine to and suspending the same within a tub.

A further object is to so mount a pounder washing-machine within a tub that the pounder can be operated by an angular lever, so that it can be reciprocated vertically and at the same time be swung laterally and so that said lever and pounder can be moved bodily from side to side or end to end of the tub, accordingly as the machine is attached to an end or a side of the tub.

A further object is to provide simple and efficient means for effecting angular adjustment of the support of the operating-lever, whereby the true vertical reciprocations of the pounder and its consequent operation at right angles to the surface of the water in the tub will be insured.

A further object is to provide ready means for permitting the removal of the pounder and its operating devices.

With these objects in view the invention consists in certain novel features of construction and combination and arrangements of parts, as hereinafter set forth, and pointed out in the claims.

In the accompanying drawings, Figure 1 is a transverse sectional view of a set tub, showing my improvements, in elevation and partly broken away, applied thereto. Fig. 2 is a plan view with the tub partly broken away. Fig. 3 is an enlarged detail view, partly in section, showing the supporting devices for the trackway. Fig. 4 is a detail view of one of the track-supporting brackets. Fig. 5 is a plan view of the trackway and slide or carrier thereon. Fig. 6 is a detail view in section, showing the mounting for the operating-lever. Fig. 7 is a bottom plan view of the sleeve 25. Fig. 8 is a detail view showing a portion of the lever, the lever-mounting, and lock-operating device for the slide or carriage. Fig. 9 is a detail view of a part of the operating-lever and the cam 42 thereon; and Fig. 10 is a detail view showing the application of the supporting-clamp to the tub, a portion of the latter being shown in front elevation.

1 represents a set or fixed tub such as now in general use in laundries, having a sloping front wall. Owing to the fact that the tub is fixed, that it is peculiar in shape, and that its proportionate dimensions are very different from those of the ordinary portable tub, it has been found impracticable to apply pounder apparatus to such fixed tubs in the manner heretofore employed with portable tubs, to which latter the apparatus could be attached at any point or at different points on the rim for the purpose of causing the plunger to reach all parts of the tub. In order that a pounder washing-machine shall be effectual, it is necessary that the operator shall be able to move the pounder to all parts of the tub, and this could not, as above stated, be accomplished in set tubs with the use of the appliances heretofore employed with portable tubs; hence the principal object of my invention.

I have found by experience that in the practical application of a pounder washing-machine to a set tub two conditions are important—viz., that the operating mechanism should be supported within the tub not far above the water-line and that an angular op-

erating-lever should be employed. The various features of construction of my improvements are adapted to these conditions, as will be readily understood from the following 5 detailed description of the apparatus.

The support 9 for the mechanism is located within the tub, preferably by means of a hanger 2, comprising two rods bent to embrace the upper end of the front wall of the 10 tub. The outer members 3 of the hanger are bent to converge, and their lower ends are connected by a coupling 3^a, through which a clamping-screw 4 is passed and made to engage the outer wall of the tub. The inner 15 arms or members 5 of the hanger 2 lie parallel with each other and parallel with the inner face of the sloping front wall of the tub, and each of said arms or members 5 is provided in one face with a series of notches 5^a. 20 As shown in the drawings, the support above referred to is made in the form of brackets, each having a sleeve 8 adjustably secured to an arm or member 5 of the hanger by means of a set-screw 7, which will be made 25 to engage any of the notches 5^a. Each bracket or support member 9 is made with a curved upper face 9^a, and from the center of the curved face of each bracket a screw 12 projects upwardly, and said screws are preferably so disposed as to project at an angle to the axis of the bracket-sleeves 8. The brackets 9 serve to support a trackway 15, which lies at points near its ends upon the curved 30 faces 9^a. This trackway may be conveniently made of a single metal rod bent upon itself to form two members 15^a 15^b, the free ends of which are connected by a suitable coupling 19. The fixed screws 12 project between the members of the trackway and receive blocks 13, having their lower faces curved concentric with the curvature of the upper faces of the brackets 9, and serve to clamp the trackway to said brackets, said blocks being firmly held to effect this clamping 35 action by means of nuts 14, secured on the upper ends of the screws 12. It is important that the trackway shall be maintained always in a horizontal position and that both members of said trackway shall be 40 in the same horizontal plane. On account, therefore, of the fact that the inclination of the front wall of the tubs may vary with different makes, and it being desirable to make the apparatus attachable to tubs of all makes, 45 it is necessary that angular adjustment of the trackway shall be provided for.

The devices above described for securing the trackway to the supporting-brackets afford ready means for easily and quickly effecting the angular adjustment above referred to, as clearly illustrated in Fig. 3, because, as will be readily seen, any lateral movement of the trackway between the concentric curved surfaces of the clamping 50 means will at once change the angle of the

trackway relative to that of the hanger and the tub front. Thus the proper position of the trackway to receive the operating mechanism can always be insured regardless of the angularity of the tub front to which the machine may be attached. By making the brackets 9 adjustable vertically the height of the trackway can be regulated according to the depth of the tub on which the apparatus may be used or the quantity of water and clothes 70 which the user may desire to employ, it being desirable in all cases that the trackway which supports the operating mechanism shall be located in comparatively close proximity to the water-line within the tub. 80

A slide or carriage 21 is mounted on the trackway 15 and is adapted to travel from end to end thereof. The slide or carriage is provided over one member of the trackway with a rotatable mounting for the operating-lever. In constructing this mounting the trackway is provided with a tubular post 23, inclosed by a revoluble sleeve 25. This sleeve is provided at its base with a flange 26, normally confined under fingers 27 on the carriage, and said flange is made with diametrically opposite notches 28 to permit the ready removal of the sleeve, together with the operating mechanism which it carries, as hereinafter explained. The sleeve 25 is provided at diametrically opposite points near its base with pintles 31, on which an operating-lever 30 is fulcrumed. This lever is angular or of the bell-crank variety and is pivotally mounted on the pintles at the elbow 90 formed by the juncture of its arms. The lever 30 comprises two parallel members secured together, and these members inclose the sleeve 25, the respective members being pivotally mounted on the respective pintles 31. The 95 stem or shaft 33 of the pounder 34 is pivotally attached at a point between its ends to the free end of the horizontal arm of the operating-lever 30, and to the upper end of said stem one end of a pitman 38 is pivoted, the 100 other end of said pitman being pivotally attached to the sleeve 25 in proximity to the upper end of the latter. 105

A handle 35 is secured to the upwardly-projecting arm of the operating-lever, said handle being inserted between the members of the lever and secured by transverse fastening devices. 110

It will be observed that with the construction and arrangement of parts above described the operating mechanism can be mounted down within a tub, thus adapting the apparatus particularly to set tubs having sloping fronts; that thus mounting the operating mechanism within the tub admits of the use of an angular operating-lever, which is very desirable; that the lever has a free rocking movement to reciprocate the pounder; that said lever also has a swinging motion, being permitted to oscillate with the 120

sleeve 25, to which it is connected, for the purpose of moving the pounder to different positions within the tub; that the lever, with its mounting and pounder, can be moved laterally from end to end of the tub by moving the carriage 21 on the trackway, and that the lever, with its mounting and pounder, can be readily removed from the tub by turning the sleeve 25 until the notches 28 align with the fingers 27.

A pin 40 passes through the tubular part 23 and is adapted to engage any one of a series of notches 18 in the trackway. The pin 40 is provided at its upper end with a head 41, which is engaged by a cam 42, so constructed that at a certain point in the movement of the operating mechanism it will raise the pin 40 and release the carriage. Thus when the lever is operated the pin 40 will lock the carriage and hold it locked until the pounder has been raised to nearly its full throw, when the cam 42 will raise the pin and release the carriage.

The stop-lock device above described would be unnecessary if the lever was always to be operated in a plane approximately at right angles to the track; but when the pounder is swung toward either end of the tub and pressure is applied the tendency of the carriage would be to move forward out of position on the track. In the reverse or upward movement of the pounder and while the suction is still in effect the carriage will be pulled back toward the operator if not locked. Such actions of the carriage without a stop check and lock would be very annoying and also unfavorably affect the working capacity of the pounder. By the stop-lock and unlock devices above described the fulcrum will be kept in one place for all working positions of the pounder among the clothes both in the downward and the first part of the upward movement and always unlocked as soon as suction releases the pounder and it is desirable to move to a new position.

The trackway upon which the operating mechanism is mounted can be readily removed, and it is also reversible—that is to say, it can be turned end for end from the position shown in the drawings—and when thus disposed the mounting for the operating mechanism will be located farther away from the front wall of the tub, thus adapting the apparatus for tubs of more than the usual width or when it is desired that the pounder shall reach close to the rear wall of the tub.

Numerous slight changes might be made in the details of construction of my invention without departing from the spirit thereof or limiting its scope, and hence I do not wish to limit myself to the exact details set forth.

The term "support" as used in the claims is intended to mean any device which will perform the functions of a support. The specific support shown in the drawings consists

of the brackets 9, and the specific means shown for sustaining this support down inside a tub consists of the hanger 2.

Having fully described my invention, what I claim as new, and desire to secure by Letters Patent, is—

1. In a washing-machine for set tubs, the combination with a support and means for sustaining said support down inside of a tub, of a rotatable mounting sustained by said support, a bell-crank lever pivoted between its ends to said rotatable mounting, the lower arm of said lever projecting laterally within the tub and the upper arm of said lever projecting upwardly above the tub, and a pounder connected to the lower arm of said lever and sustained thereby.

2. In a washing-machine for set tubs, the combination with a support and means for holding the same down into a tub, of a rotatable mounting sustained down in the tub by said support, and an angular lever pivoted to said rotatable mounting and a pounder carried by one arm of said lever, whereby said lever can be oscillated on its pivot and the arm carrying the pounder swung laterally within the tub.

3. In a washing-machine for set tubs having inclined fronts, the combination with a support, means for sustaining the same within the tub, an angular lever, and a pounder carried by one arm of the angular lever, of devices connecting the apex of said lever with the support and permitting the lever to be operated within the tub in two directions at right angles to each other.

4. The combination with a support of a reversible trackway comprising two members, mounted on said support, a carriage on the trackway, a lever, a mounting for the lever on the carriage over one member of the trackway and a pounder attached to said lever.

5. The combination with a trackway, a support therefor and a carriage thereon, of a pivoted lever mounted on the carriage, a pounder attached to said lever, and means for automatically locking and unlocking said carriage when the lever is operated.

6. In a washing-machine for set tubs, the combination with a hanger, of a vertically adjustable support attached thereto, a bell-crank lever, a rotatable mounting for said lever sustained by said support, and a pounder attached to the arm of said lever which projects laterally from the rotatable mounting within the tub.

7. In a washing-machine for set tubs, the combination with a hanger, a bell-crank lever and a pounder attached to the lever, of a rotatable mounting sustained by said hanger and having pivotal connection with the apex of the lever and means for effecting angular adjustment of said mounting relative to the hanger within the tub.

8. The combination with a support and

means for sustaining it down in a tub, of a trackway mounted on said support so as to be disposed inside the tub, a slide on the trackway, a bell-crank lever mounted on said slide, 5 a pounder attached to the lever and means for effecting angular adjustment of the trackway on the support.

9. The combination with a support and means for sustaining it within a tub, of an angular lever, a mounting for said lever sustained by said support, means for effecting angular adjustment of said mounting and a pounder attached to one arm of said lever.

10. The combination with a trackway, a carriage thereon and a support for the trackway, of means for effecting angular adjustment of the trackway, a pivoted lever supported by the carriage and a pounder attached to said lever.

11. In a washing-machine, the combination with a support to be secured down in the tub, a track on the support, a slide fitted to the track and movable thereon, a bell-crank lever pivotally supported on the slide having 25 a lower arm extending laterally in the tub and an upper arm upwardly extending above the tub, and a pounder on the end of the lateral arm.

12. In a washing-machine, the combination with a support to be secured down in the tub, of a track on the support, a slide fitted to the track, a substantially vertical post on the slide, a sleeve fitted to the post and turning thereon, a bell-crank lever pivotally secured 35 to the sleeve and rocking thereon, a pounder on the lower arm of the bell-crank lever and a handle on its upper arm.

13. In a washing-machine, the combination with a support to be secured down in the tub, of a track on the support, a slide fitted to the track, a substantially vertical post on the slide, a sleeve fitted to the post and turning thereon, a bell-crank lever pivotally secured to the sleeve and rocking thereon in substantially a vertical plane, a pounder on the lower arm of the lever, a handle on the upper arm of the lever, means to lock the slide to the track when the pounder is being depressed and means automatically to unlock the slide 50 when the pounder is being elevated.

14. In a washing-machine the combination with a support to be secured down in the tub, of a track on the support, a slide fitted to the track, a substantially vertical post on the slide, lips on the slide adjacent to the foot of the post, a sleeve fitted to the post and turning thereon, a notched flange at the lower end of the sleeve to engage with the lips, the notches being arranged to register with the 55 lips when the pounder is turned against the side of the tub, a bell-crank lever pivotally secured to the sleeve and rocking thereon in substantially a vertical plane, the pounder on the lower arm of the lever and a handle on the 60 upper arm of the lever.

15. In washing-machine for set tubs having inclined fronts, the combination with a support to be secured down in the tub on the inner surface of the front, of a horizontal track carried on the support, a slide fitted to the track and longitudinally movable thereon, a substantially vertical post on the slide, a sleeve fitting the post and turning thereon, an angular lever pivotally fixed at its elbow on the sleeve and rocking in substantially a vertical plane, and a pounder on the end of the lower arm of the lever.

16. In a washing-machine for set tubs having inclined fronts, the combination with a support to be secured down in the tub on the inner face of the front, of a substantially horizontal track carried on the support, means to adjust the track angularly thereon, a slide fitted to the track to slide thereon, a substantially vertical post on the slide, a sleeve fitting the post and turning thereon, an angular lever pivotally secured on the sleeve and rocking thereon in substantially a vertical plane, said lever having a lower arm extending laterally in the tub and an upper arm extending upwardly out of the tub, and a pounder on the end of the lower arm.

17. In a pounder washing-machine for set tubs, having inclined fronts, the combination with a support to be secured down in the tub on the inner face of the front, of a substantially horizontal track carried on the support, means to adjust the track angularly thereon, a slide fitted to the track to slide thereon, a substantially vertical post on the slide, a sleeve fitting the post and turning thereon, an angular lever pivotally secured on the sleeve and rocking thereon in substantially a vertical plane, said lever having a lower arm extending laterally in the tub and an upper arm upwardly extending, a pounder on the lower arm, a handle on the upper arm extending substantially vertically out of the tub, means to lock the slide to the track while the pounder is being depressed, and means automatically to unlock the slide when the pounder is being raised.

18. In a pounder washing-machine, the combination with the clamping-frame having legs extending down into the tub and means for clamping the frame on the tub, of supporting-brackets means for securing the brackets in position on the legs, a track supported and angularly adjustable on the brackets, means to secure the track on the brackets, a slide fitted to the track, an angular lever pivotally fulcrumed on the slide, and having an upper upwardly-extending arm, and a lower laterally-extending arm, and a handle secured to the upwardly-extending arm and extending above the tub.

19. In a pounder-washing machine, the combination with the clamping-frame having arms arranged outside of the tub, legs extending down into the tub and means for clamp-

ing the frame on the tub, of supporting brackets, means for securing the brackets in position on the legs, a track supported on the brackets, a slide fitted to the track, a substantially vertical post on the slide, a sleeve fitting the post and turning thereon, an angular lever sustained on the sleeve by pivots at the lever-fulcrum so as to rock on the sleeve, said lever having a lower arm and an upper arm, the pounder on the lower arm to operate in the tub, and an operating-handle on the upper arm extending upwardly out of the tub.

20. In a washing-machine for set tubs, the combination with a support and means for sustaining it within a tub, of an angular lever, a mounting for said lever sustained by said support, means for effecting angular adjustment of said mounting, a pounder having a stem pivotally attached between its ends to an arm of said lever, and a rod or pitman pivotally attached at one end to the upper end of the stem of the pounder and at the other end to the mounting of the angular lever.

21. In a washing-machine for set tubs, the combination with a support having a curved upper face, and means for sustaining said support within a tub, of a trackway mounted on the curved face of said support, means for clamping the trackway on said curved face of

the support, a mounting sustained by said trackway, a lever pivoted to said mounting, and a pounder attached to said lever.

22. In a washing-machine for set tubs, the combination with a support having a curved upper face, and means for sustaining said support within a tub, of a trackway mounted on the curved face of the support, a screw projecting upwardly from the curved face of the support, a block mounted on said screw and having a curved lower face parallel with the curved upper face of the support, a nut on the screw, a mounting on the track, a lever pivoted to said mounting and a pounder attached to the lever.

23. In a washing-machine for set tubs, the combination with a post and a device to be disposed within the tub for supporting said post, of fingers on said post-supporting device, a sleeve mounted on said post and having a notched flange at its base normally confined under said fingers, whereby said sleeve can be readily removed from the post, a lever pivoted to the sleeve and a pounder carried by said lever.

In testimony whereof I affix my signature in presence of two witnesses.

CYRUS A. DODGE.
